UNITED STATES PATENT OFFICE.

OTTO A. HOKANSON, OF WOODSTOCK, ILLINOIS, ASSIGNOR TO WOODSTOCK TYPE-WRITER COMPANY, OF WOODSTOCK, ILLINOIS, A CORPORATION OF ILLINOIS.

PLATEN-CARRIAGE MECHANISM FOR TYPEWRITERS.

1,427,470..

Specification of Letters Patent. Patented Aug. 29, 1922.

Application filed June 12, 1920. Serial No. 388,420.

To all whom it may concern:

Be it known that I, OTTO A. HOKANSON, a citizen of the United States, residing at Woodstock, in the county of McHenry and 5 State of Illinois, have invented certain new and useful Improvements in Platen-Carriage Mechanism for Typewriters, of which the following is a specification.

This invention relates to platen carriage 10 mechanism and especially to an anti-creep- ing device for the carriage bearing balls, and has for its object the provision of a mechanism of the character named which shall be of improved construction and oper- 15 ation.

The invention is exemplified in the combi- 20 nation and arrangements of parts shown in the accompanying drawings and described in the following specification, and it is more particularly pointed out in the appended 25 claims.

In the drawings,

Fig. 1 is a top plan view of an anti-creep- 25 ing ball retainer frame forming a part of the present invention;

Fig. 2 is an élévation of the frame shown in Fig. 1;

Fig. 3 is a transverse sectional view of a 30 platen carriage having the present invention applied thereto; and

Fig. 4 is a vertical section substantially on line 4—4 of Fig. 3.

In the form of platen carriage illustrated in Figs. 3 and 4, the numeral 10 designates 35 the bed plate of the platen carriage provided with V-ways 11 at the front and rear edges thereof. The platen carriage comprises a movable plate 12 having V-ways 13 arranged to cooperate with the ways 11 and between 40 the ways 11 and 13 bearing balls 14 are interposed. The carriage plate 12 may be made in two sections adjustably connected together by cap screws 15 which permits of easy assembling and also provides for an ad- 45 justment of the bearings on the balls 14. A

ball retainer frame 16, shown in detail in Figs. 1 and 2, is provided for holding the balls 14 in proper position in the ways 11 and 13 and is arranged to travel between 50 the bed plate 10 and the carriage plate 12. When the carriage 12 is moved along the bed 10 it is apparent that the linear move- 55 ment of the balls 14 will normally be half as great as that of the carriage but in prac- tice there is a tendency for the balls to creep

or work toward one end or the other of the ways 11 during continued movement of the carriage back and forth upon its ways. In order to prevent a creeping movement of this kind, the frame 16 is provided with a 60 projection 17 on which a toothed wheel 18 is journaled in position to engage a rack 19 secured to the carriage bed plate 10, as shown in Figs. 1 and 4. A similar rack 20 is secured to the platen carriage plate 12 so 65 that when the carriage is moved back and forth upon its bed, the toothed wheel 18 will travel between the two relatively movable parts at a speed equal to half the speed of the carriage upon its bed plate. Since the 70 wheel 18 is journaled on the frame 16, it is apparent that the frame will be constrained to move in unison with the wheel thus im- parting to the balls 14 the correct speed relative to the movement of the ways 11 75 and 13.

The platen carriage is moved by the usual form of spring drum or by any well known and approved mechanism and is controlled by an escapement wheel 21 having a pinion 80 22 which meshes with a rack, not shown but connected with the movable carriage. Stops 23 and 24 are provided for limiting the movement of the carriage on its bed, thus preventing the balls 14 from being carried 85 beyond the ends of the ways 11 and 13.

As will be seen from the drawings, the frame 16 may be stamped from sheet metal with cross bars 25 having reinforcing ribs 26 formed thereon. The balls 14 are held in 90 circular openings in upright flanges 27 bent downwardly from the front and rear bars 28 and 29 respectively of the frame 16. It will be seen that the frame is simple and of light construction and that it fits between the 95 parts of the platen carriage without inter- fering with the working mechanism of the carriage and without requiring additional space.

I claim:

1. In a typewriter, a platen carriage sup- 100 port comprising a frame plate having later- ally projecting guideways at the opposite edges thereof, a platen carriage comprising a plate arranged parallel with said frame plate and having laterally projecting guide- 105 ways overlapping the guideways on said frame plate and forming ball races there- with, a ball retainer comprising a sheet metal frame interposed between said plates 110

and having offset flanges projecting between said guideways for engaging roller bearings in said ball races, oppositely disposed racks supported by said parallel plates, and a gear 5 wheel for engaging said racks journaled on said sheet metal frame and arranged parallel with the roller engaging flanges thereof so that the rollers in said ball races will be constrained to travel a distance equal to half 10 the relative movement between said parallel plates.

2. In a typewriter, a platen carriage frame comprising a horizontally disposed plate having upstanding flanges at opposite edges 15 thereof, said flanges being bent into V-shape to form guideways at their sides, a platen carriage comprising a plate arranged parallel with said frame plate and having downwardly extending flanges at the edges there- 20 of overlapping the flanges on said frame

plate and cooperating therewith to form raceways for roller bearings, a bearing retainer comprising a sheet metal frame positioned between said parallel plates and adjacent the uppermost one thereof, said frame 25 having downwardly bent flanges extending between the parts of the raceways, roller bearings in said raceways engaged by said downwardly bent flanges, racks secured to said parallel plates, an ear extending downwardly from said sheet metal frame, and a pinion journaled on said ear in a plane substantially parallel with said bearing engaging flanges, said pinion meshing with said racks for controlling the movement of said 30 bearing rollers.

In testimony whereof I have signed my name to this specification on this 1st day of June A. D. 1920.

OTTO A. HOKANSON.
